UNITED STATES PATENT OFFICE.

WILLIAM H. VOSS, OF DAVENPORT, IOWA.

DOOR.

Application filed September 13, 1920. Serial No. 409,753.

To all whom it may concern:

Be it known that I, WILLIAM H. Voss, of Davenport, Iowa, have invented certain new and useful Improvements in Doors, of which 5 the following is a specification.

My invention relates to washing machine doors, and more particularly to a door of the kind which will reduce to a minimum the amount of danger incident to the use of 10 an oscillating tub washing machine, this application being a continuation in part of my prior application, Serial No. 294,235, in which was disclosed and claimed the generic idea of a swinging door used with an oscillating tub washing machine to prevent injury to the hands of a person operating the 15 machine.

Among the objects of my invention are the following: To provide means in connection 20 with an oscillating tub to prevent injury to a person by reason of a portion of his body getting caught between the tub and the enclosing walls; to provide a machine of the character stated with a door 25 whereby access may be had to the interior of the machine; to provide in a machine, having a laterally swinging door, an auxiliary door connected with the first named door, so arranged as to prevent injury to 30 a person when he or she gets caught between said door and a moving part; and such further objects, advantages and capabilities as will later more fully appear.

My invention further resides in the combination, construction and arrangement of 35 parts illustrated in the accompanying drawings, and while I have shown therein a preferred embodiment, I desire the same to be understood as illustrative only and not as 40 limiting my invention.

In the accompanying drawings illustrating this invention, Figure 1 is an end view of a washing machine having a pair of doors constructed in accordance with my 45 invention;

Figure 2 is a fragmentary sectional view to show in detail the upper and lower parts of the door;

Figure 3 is a side elevation of the machine to show a face view of one of the doors;

Figure 4 is a fragmentary plan view of one side of a machine comprising my invention; and

Figure 5 is a horizontal section substan-

tially along the plane indicated by the line 5—5, Figure 3.

Referring more in detail to the annexed drawings, 1 designates the washing machine in its entirety, 2 the oscillating tub of the 60 machine, and 3 the doors, according to my invention. The machine is supported upon suitable casters, which are secured to the corner posts 4 of the machine. Connecting adjacent posts 4 are the side pieces 5, which 65 serve to hold the posts in position.

The doors 3 are secured to diagonally opposite posts 4 and are hinged at 11 to swing on substantially vertical axes, thus providing means whereby access may be readily had 70 to the mechanism housed within the interior of the frame. The edge of a door opposite that on which it swings is provided with a fastening means 6, adapted to engage a post 4, as shown most clearly in Figure 5, to hold 75 the door in closed position. Rods or bars 7 extend between the posts 4 at opposite sides of the machine to hold the same in proper relative position.

Secured to the upper edge of the main 80 section of the door, as by spring hinges 8, is an auxiliary door 9, which is provided with a hook 10 to engage over the bar 7 and assist in holding the main door, and there- 85 with the auxiliary door, in closed position.

It is obvious that if the door were made as a unitary structure and were hinged at one edge as is the lower portion, a person's hand, if caught between the door and oscillating tub near the hinged edge would have 90 to stand considerable more pressure before the latch of the door would yield and allow the same to open than if the person's hand were caught near that edge upon which the fastening means is located. On the other 95 hand, with the top portion or auxiliary door hinged upon a horizontal axis and having both its ends receding from the oscillating tub at the same rate, it would make no difference in the amount of pressure necessary 100 to force this auxiliary door away from the tub, whichever end of the door were pressed.

It will therefore be seen that the door of my invention is a safety device which reduces very materially the likelihood of injury resulting from a person getting caught between the tub and door. It is, of course, understood that the specific description of structure set forth above may be departed 105 from without departing from the spirit of 110

my invention as set forth in this specification and the appended claims.

Having described my invention:

I claim:

- 5 1. In a washing machine, a support, a movable tub thereon, a door hinged to the support, an auxiliary member hinged along an edge thereof to the door and being normally near the tub, and means for normally holding the auxiliary member in closed position near the tub but capable of being swung on its hinge by a relatively small pressure anywhere along the edge opposite that on which it is hinged.
- 10 15. 2. In a washing machine, a support having side walls, a movable tub thereon, a closure having a lower portion, an upper portion hinged to said lower portion and adapted to swing away from the tub, and 20 means normally holding the hinged upper portion in closed position, said means being yieldable to permit the hinged upper portion to open outwardly by pressure between said tub and upper hinged portion at any 25 point along the free edge of the latter.
- 30 3. In a washing machine, a support having sides, an oscillating tub mounted on the support, a two part closure, one part of said closure being hinged to one of the sides, and 35 the other part being hinged to said one part, means normally holding said closure in closed position, said other part of the closure being adapted to move outwardly away from the tub when excess pressure is applied thereto, and to normally stand adjacent the tub in the absence of such pressure.
- 40 4. In a washing machine, a frame work, an oscillating tub thereon, and a door connected therewith and pivotally mounted to swing outwardly on a substantially hori-

zontal axis, said door being normally proximate to the end of the tub and being provided with means to hold the same normally closed but capable of being swung outwardly from the frame by a comparatively small pressure at any point along its edge opposite that on which it is pivoted, when an obstruction enters between the tub and the door.

5. A casing, an oscillatory tub mounted thereon, said casing extending around the ends of the tub and having end doors comprising main and auxiliary sections, each main section being hinged to the casing and each auxiliary section being hinged to the main section and being normally proximate to an end of the tub when the tub oscillates, said auxiliary sections and said casing having means for normally holding the auxiliary sections in closed position, but yielding to permit the auxiliary sections to open upon the entry of obstructions between the ends of the tub and the auxiliary sections.

6. A rectangular open top casing, a tub mounted for oscillation in the top of said casing, one side of said casing at one end of the tub being formed of an upper and a lower section, the lower section being hinged at one of its vertical edges to an adjacent side, and the upper section connected to the upper edge of the lower section by light spring hinges, and normally slightly spaced from the end of the tub.

In witness whereof, I hereunto subscribe my name to this specification in the presence of two witnesses.

WILLIAM H. VOSS.
